HEATER

Morris L. Markel, Tonawanda, and Cuthbert Grant, Eggertsville, N. Y., assignors to Markel Electric Products, Inc., Buffalo, N. Y., a corporation of New York

Application August 1, 1957, Serial No. 675,680

4 Claims. (Cl. 219—39)

This invention relates to heaters, and more particularly to an electric wall heater having an enclosed blower means.

The heater of the present invention is especially well suited for mounting in a wall wherein the front surface of the heater will be substantially flush with the surface of the wall. The heater utilizes both radiant and forced convection heating principles, and among the features which characterize the invention, is the manner of directing air flow through the heater to form two air streams, one of which passes over the rear surface of a reflector and outwardly of the heater, the other of which passes about the heater controls for the cooling thereof during heater operation. Another feature relates to means for directing the heater air stream outwardly from the heater to avoid damage to a papered wall surface. Still another feature resides in the arrangement of the control chamber wherein cooling air is jetted downwardly through openings formed in the underside of a forwardly projecting nose located on the front surface of the heater.

The main object of this invention is to provide an electric heater which utilizes both radiant and forced convection principles for heating.

Still another object is to provide an electric heater which will automatically maintain a predetermined room temperature.

Another object of this invention is to provide an electric heater wherein air flow therethrough is divided into two streams, one for cooling the heater controls, the other of which passes over the rear surface of a reflector prior to being blown from the heater.

A further object of the invention is to provide an electric wall heater wherein the air being blown from the heater is deflected so that it does not blow upon the surrounding wall surface.

These and further objects and features of the invention will become more apparent from the following description and the accompanying drawing wherein:

Fig. 1 is a front view of a heater embodying the principles of the invention;

Fig. 2 is a section view generally as seen along line 2—2 in Fig. 1;

Fig. 3 is a section view generally as seen along line 3—3 in Fig. 2;

Fig. 4 is a section view generally as seen along line 4—4 in Fig. 2; and

Fig. 5 is a section view generally as seen along line 5—5 in Fig. 2.

Referring now to the drawing, numeral 6 identifies a heater unit representing an embodiment of the invention, which heater includes a front panel 7, a wall insert box 8, side panels 9 and a baffle panel 11. A reflector 12, having curved sections 13 and 14 extending horizontally within the heater, opens unto an opening 16 formed in the front panel 7. Three tie rods 15 are used to maintain the reflector within the box 8. A screen, or guard 17 is arranged in the opening 16, the upper end

2

of the guard being maintained by the baffle panel 11, while the lower end is affixed to the front panel by fastening means, such as screws 18. Extending horizontally within, and in spaced relation to the curved sections 13 and 14 of the reflector 12, are electrical heater elements 19, each of which consists of a resistance wire wound upon a ceramic core.

Located in the lower region of box 8 is an electric motor 21, having a fan 22 which functions to draw air into the box 8, via a grille 23 formed in the front panel 7, and to blow the air upwardly behind the reflector 12 and from where it is directed out of the box through the upper part of the guard 17. A venturi plate 25 is arranged about the fan 22 for channeling the incoming air stream. Part of the upward flowing air passes through a hole 24 formed in the upper surface of the baffle panel 11 and enters a chamber 26 in which control elements 27 and 28 are located. The air stream passes about the control elements, to thereby cool them, and leaves the chamber 26 downwardly via holes 30 formed in a forwardly projecting nose 33, arranged on the front panel 7.

The control element 27 is operable to establish an electrical circuit through the heater elements 19 and the motor 21. Control element 28 is a thermostatically controlled rheostat operable for completion of the electrical circuit through the heater elements 19 and electric motor 21. The thermostat control 28 is operated by a liquid filled thermometer-like bulb 29, located in the air stream behind the fan 22. The control element 28 may be set to provide and maintain a predetermined intake air temperature; for example, if the control is set for say 80°, the circuit in the control element 28 will be open when the incoming air stream exceeds said predetermined temperature, to thereby discontinue operation of the heater unit. However, once the air temperature drops below the preset temperature, the circuit through the control element 28 will be completed, and heater operation will take place.

A pair of brackets 31 are secured to the top and bottom of box 8 whereby the heater may be mounted within a wall between the studs thereof. A hole 32 is provided in the top surface of the box 8, which may be used for bringing in the power lines for connection to the control elements.

From the foregoing it will be seen that the heater of the invention may be conveniently installed in a wall, and may be operated for automatically regulating the air temperature in a room. The arrangement of the air flow through the heater to form two air streams, one of which is used for cooling the heater controls, represents an efficient manner for operation of the heater. Other features as described serve to fulfill the objectives as set forth in the beginning of this disclosure.

The foregoing description has been given in detail without thought of limitation since the inventive principles involved are capable of assuming other physical embodiments without departing from the spirit of the invention and the scope of the appended claims.

What is claimed is:

1. A heater comprising heater elements arranged in a reflector, a blower means for moving an air stream through the heater and around the reflector on the side opposite the heater elements, control means for operation of the heater elements and blower means, and means to divide the air stream into two paths one of which flows past the control means.

2. An electric heater comprising heater elements arranged in a reflector, a blower means for moving an air stream through the heater and around the reflector on the side opposite the heater elements, control means for operation of the heater elements and blower means, a thermostat means for operation of the control means in

accordance with the air stream temperature, and means to divide the air stream into two paths one of which flows past the control means.

3. An electric heater comprising electrical heater elements, a reflector for partially enclosing the heater elements, a motor having a fan which is operable for moving an air stream through the heater and around the reflector on the side opposite the heater elements, a pair of control elements for operation of the heater elements and the motor, one of said control elements adapted to disrupt flow of electric current to the heater elements and motor when the temperature of the air stream exceeds a predetermined value, and means to divide the air stream into two paths one of which flows past the control elements.

4. An electric wall heater comprising a box, a front panel secured to the box and being formed to provide an opening having a covering grille, a pair of electrical heater elements horizontally disposed in said box, a reflector having curved portions spaced from the heater elements and adapted to reflect heat rays from the heater elements outwardly of the box via the grille covered opening, a motor having a fan operable for moving an

air stream from a venturi opening at the lower part of the heater, past the back of the reflector, and outwardly of the heater via the grille covered opening, a baffle plate for directing the air stream upwardly in the heater, and 5 a pair of electrical control elements arranged in a chamber formed at the top of the heater, said control elements adapted for completing electric circuits through the heater elements and the motor, one of said control elements having a thermostat means arranged in said air stream adapted to disrupt the circuit through the control element when the temperature of the air stream exceeds a predetermined value, said baffle plate being arranged to direct a certain part of the air stream through the control element chamber.
